CLAIM

The ornamental design for a computer screen with graphical user interface, as shown and described.

DESCRIPTION

FIG. 1 is a front view of a first embodiment of a computer screen with graphical user interface.

FIG. 2 is a front view of a second embodiment of a computer screen with graphical user interface.

FIG. 3 is a front view of a third embodiment of a computer screen with graphical user interface; and,
FIG. 4 is a front view of a fourth embodiment of a computer screen with graphical user interface.

The computer screen shown in broken lines forms no part of the claimed design. The portions of the graphical user interface shown in broken lines form no part of the claimed design.

1 Claim, 4 Drawing Sheets

FIG. 1

FIG 2

FIG. 3

FIG. 4
